[57] CLAIM

The ornamental design for an electrosurgical pencil, as
shown and described.

DESCRIPTION

FIG. 1 is an isometric view of an electrosurgical pencil with
the cord, plug, and electrode shown in phantom lines for
illustrative purposes only and form no part of the claimed
design;

FIG. 2 is a plan view of the electrosurgical pencil;

FIG. 3 is a side view of the electrosurgical pencil; and.

FIG. 4 is a bottom view of the electrosurgical pencil.
